[57] CLAIM

The ornamental design for a portable cooler or the like, as shown and described.

DESCRIPTION

FIG. 1 is a perspective view of a portable cooler or the like, showing our new design;

FIG. 2 is a side elevational view thereof;

FIG. 3 is a front elevational view thereof; and

FIG. 4 is a rear elevational view thereof.

FIGS. 2 through 4 are shown fragmentarily for convenience of illustration.

The bottom of the cylindrical body is plain and unornamented.

FIG. 1

FIG. 2

FIG. 3

FIG. 4
